J. F. ALTAFFER.

RAIL TIE.

APPLICATION FILED APR. 20, 1920.

1,349,310.

Patented Aug. 10, 1920.

UNITED STATES PATENT OFFICE.

JOHN F. ALTAFFER, OF ALINE, OKLAHOMA.

RAIL-TIE.

1,349,310.

Specification of Letters Patent. Patented Aug. 10, 1920.

Application filed April 20, 1920. Serial No. 375,235.

To all whom it may concern:

Be it known that I, JOHN F. ALTAFFER, citizen of the United States, residing at Aline, in the county of Alfalfa and State of Oklahoma, have invented certain new and useful Improvements in Rail-Ties, of which the following is a specification.

This invention relates to improvements in rail ties having means whereby rails may be securely held in position.

An important object of this invention is to provide a rail tie having means whereby the rails may be detachably secured to the same without the necessity of employing such fastening devices as spikes.

A further object of this invention is to provide a rail tie of the class described which is durable, efficient in use and cheap to manufacture.

Other objects and advantages of the invention will be apparent during the course of the following description.

In the accompanying drawing forming a part of this application and in which like numerals are employed to designate like parts throughout the same,

Figure 1 is a longitudinal sectional view through the improved rail tie,

Fig. 2 is a similar view, illustrating the rail engaging means in use,

Fig. 3 is a plan view of a portion of a track having the improved rail ties,

Fig. 4 is a vertical transverse section taken on line 4-4 of Fig. 2.

In the drawing wherein for the purpose of illustration is shown a preferred embodiment of the invention, the numeral 10 generally designates the improved rail tie which is preferably of metal cast or otherwise formed into the desired shape.

As illustrated particularly in Figs. 1 and 2, the improved rail tie is of hollow formation and has its upper side 12 provided with spaced rail engaging devices 14 having offset flanges 15 adapted for overhanging the base of the rails and engaging the outer sides of the webs of the same.

With particular reference to Fig. 3, it will be noted that a pair of spaced fastening devices 17 are employed for securing each of the rail engaging devices 14 to the upper side of the tie so that pivotal movement of each of the rail engaging devices upon the tie is prevented. The means employed for detachably securing the rails to the tie in spaced parallel relation comprises arms 20

and 22 arranged in longitudinal alinement and having their adjacent ends formed with interfitting tongues and grooves 24 and 26. The outer portions of the arms 20 and 22 are formed with slots 28 having their upper and lower side walls 30 and 32 respectively inclined outwardly so that the upper walls 30 may be engaged with the bases of the rails and so that the lower walls 32 may be flatly engaged with the under side of the top 12 of the tie when the arms are in their operative or lowermost position.

With reference to Figs. 1 and 2, it will be noted that the space between the rails is slightly less than the combined length of the arms 20 and 22 so that when the arms are moved downwardly the same must spring or yield slightly so as to assume the position illustrated in Fig. 2. When the arms 20 and 22 have been moved downwardly so that their adjacent portions engage the bottom wall 36 of the tie, the outer portions of the arms are securely engaged with the rails and the adjacent portions of the tie so that the rails are prevented from lateral movement with relation to the tie. As the upper inclined wall 30 of the sockets 28 flatly engages the upper side of the base of each rail, the rail is prevented from partaking of any movement as the result of the movement of rolling stock over the same. When the arms 20 and 22 have been positioned so that their adjacent portions are disposed below the plane of the upper side of the tie, a longitudinal slot 40 through which the same pass, prevents transverse movement of the arms. In other words, the connection between the arms 20 and 22 is prevented from being broken from contact of the arms with the side walls of the longitudinal slot 40.

When it is desired to release the arms 20 and 22, their adjacent ends are moved upwardly by manually elevating loops 42 formed on the upper sides of the arms. In carrying out the invention the loops 42 may be formed integral with the arms or may be secured to the adjacent ends of the same by any suitable fastening means. If desired, a lever may be extended through the loops for elevating the same.

With reference to the foregoing description it will be noted that the rails may be securely and detachably connected to the tie without the necessity of employing such fastening devices as spikes. It will also be

noted that since the device is preferably constructed of metal, the possibility of decay is obviated.

It is to be understood that the form of 5 the invention herewith shown and described is to be taken as a preferred embodiment of the same and that such minor changes in construction and arrangement of parts may be made as will remain within the spirit of 10 the invention and the scope of what is claimed.

Having thus described the invention, what is claimed as new is:

A rail tie comprising a hollow body having 15 a top wall provided with a longitudinal slot, a pair of rail engaging members secured to said body adjacent said slot, and a

pair of arms having their adjacent ends provided with an interlocking tongue and groove connection, the combined length of 20 said arms being greater than the length of said slot whereby said arms have their inner portions moved downwardly into engagement with the bottom of a tie, the outer portions of the same will be securely engaged 25 with the rails, the outer portions of said arms being formed with sockets having their upper and lower sides inclined downwardly so as to firmly engage the bases of the rails and the under side of the top wall 30 of the body.

In testimony whereof I affix my signature.

JOHN F. ALTAFFER. [L. S.]
